STOP MOTION FOR KNITTING MACHINES
AND THE LIKE

William Ewart Stanley and Cyril Houghton
Edwards, Spondon, near Derby, England, as-
signors to Celanese Corporation of America, a
corporation of Delaware

Application May 13, 1941, Serial No. 393,168
In Great Britain June 7, 1940

9 Claims. (Cl. 66—166)

This invention relates to stop motions for knitting machines and the like, and is particularly concerned with stop or detector motions for warp knitting machines.

According to the present invention a stop or detector motion for a knitting machine or the like comprises a photo-electric cell, means for traversing said cell repeatedly across a fabric being formed on the machine and close to the line at which said fabric is being knitted, means for directing light coming from said fabric into said cell, and operative means controlled by said cell and adapted to act on undue variation of the amount of light entering said cell by reason of faulty fabric. By this means the whole of the fabric may be traversed by the cell and if a thin or thick place should be encountered at any point in the fabric, due to a missing thread, or an extra thread, or any other fault, the light transmitted through or reflected from the fabric, and consequently the light entering the cell, will alter in intensity and the operative means will act, either to stop the machine or to give a warning signal.

The photo-electric cell employed for the purpose of the present invention is preferably enclosed by a suitable casing having a narrow slit which faces the fabric and is close to the surface thereof as the cell is traversed across the fabric. The slit, which should extend parallel to the length of the fabric being formed, should be of sufficient length to cover the short length of fabric formed in the time between successive passages of the cell, so that every part of the fabric is covered. In conjunction with the cell, and connected therewith by a suitable cable for supplying current to the cell, a suitable valve amplifier and relay may be employed so that the small variation of current occurring when the resistance of the cell varies on account of a change of light intensity may be sufficiently intensified to be used for stopping the machine or giving the required signal. The sensitivity of the cell and associated mechanism should, of course, not be so high as to operate as a result of any variations in opacity that may be expected in a satisfactory fabric, and it may be necessary to make the sensitivity adjustable to deal with fabrics of different types and/or patterns. This may be done by adjusting the width of the slit, and/or by suitable resistances in the cell or relay circuit.

The light by which the photo-electric cell is actuated may be supplied from a source either on the same side of the fabric as the cell, or on the opposite side, and either in the form of a general illumination of the fabric, or in the form of

a focused illumination travelling with the cell. Where the light source is on the same side of the fabric as the photo-electric cell, use may be made of the reflection of the light from the fabric back into the cell, or alternatively a mirror may be disposed on the opposite side of the fabric to reflect the light back into the cell. In the first case the light entering the cell does not pass through the fabric, but is reflected once by the fabric itself and in the second case the light passes twice through the fabric before entering the cell.

For the purpose of traversing the photo-electric cell and if necessary the source of light, across the fabric a traversing carriage may be employed, provided, in the case of straight bar machines, with a suitable reversing mechanism. The stop mechanism according to the invention forms a convenient unit that may readily be attached to a straight bar machine such as a warp knitting machine. The mechanism usually provided on such machine for stopping the machine may be adapted, by means of suitable electrical and mechanical connections, to stop the machine under the control of the device. The only other modification necessary to the machine is the provision of one or more rails or bars across the width of the machine on which the traversing carriage may run, and the provision of the necessary driving mechanism for the carriage. The device is particularly convenient in warp knitting machines in which the threads are fed by two or more guide bars. In such machines a mechanical detector is apt to fail where a thread is missing in one bar, since the continuity of the fabric structure is maintained by the threads of other bar or bars and no actual hole, such as could be detected by mechanical means, is formed in the fabric. With the device according to the present invention however, notwithstanding the continuity of the fabric structure, the fabric becomes more transparent where a thread is missing, so that the device according to the present invention is especially well adapted to deal with such cases.

By way of example two forms of stop motion mechanism suitable for use on a straight bar warp knitting machine will now be described in greater detail with reference to the accompanying drawings, in which

Figure 1 is a side elevation;
50 Figure 2 is a front elevation of one form of mechanism;

Figure 3 is a diagrammatic side elevation of a warp knitting machine showing the application of the mechanism shown in Figures 1 and 2;

Figures 4 and 5 are a side elevation and a front

elevation respectively of a further form of mechanism; and

Figure 6 shows a detail of the mechanism shown in Figures 4 and 5.

Referring to Figures 1 to 3 the knitting elements of the machine are shown in Figure 1, i. e., the needles 1, the sinkers 2, the presser 3, and the guides 4 of a two-bar warp knitting machine. The guides 4 lead the warp threads 5 to the needles 1 by which the warp threads are knitted into the fabric 6 which proceeds to a take-up device 7 and is wound in a roll 8. On its way from the needles 1, the fabric 6 passes over a mirror 9 extending the whole length of the machine and above the fabric 6 parallel to the mirror 9 is a threaded shaft 10 mounted in bearings 11 in an extension 12 to the side frame 13 of the machine.

The threaded shaft 10 is driven from the hand-wheel shaft 14 of the machine. For this purpose pulleys 15, 16 and a belt 17 are provided which convey the drive to a bevel gear 18 secured to the pulley 16, and the bevel gear 18 engages with a bevel gear 19 mounted on a shaft 20 carrying a further bevel gear 21 engaging with two bevel-gears 22, 23 loosely mounted on the plain end of the shaft 10. One or other of the bevel gears 22 is clutched to the shaft 10 by the provision of clutch cones 24, 25, secured to the gears 22, 23 and a clutch member 26 splined to the shaft 10 and brought into engagement with one or other of the clutch cones 24, 25 by means of a fork 27 mounted on a shaft 28 parallel to the threaded shaft 10.

Resting on the threaded shaft 10 is a carriage 29 which is cut with a thread engaging with the threads of the shaft 10, so that it may be driven to and fro by the rotation of the shaft 10 alternately in opposite directions. The carriage 29 engages only with the upper side of the threaded shaft 10, which enables the shaft to be supported underneath at several points along its considerable length. Depending from the carriage 29 are two rods 30 to which are secured a lamp 31 throwing a focused beam of light on the mirror 9, and a photo-electric cell 32 adapted to receive the beam of light as it is reflected from the mirror 9 after passing twice through the fabric 6. The carriage 29 is guided and located by means of two upwardly extending lugs 33 engaging with the shaft 28. These lugs also serve to engage a stop member 34 secured to the shaft 28 whereby, when the carriage 29 reaches the end of its motion, the shaft 28 is moved longitudinally carrying with it the fork 27. The movement of the fork 27 disengages the member 26 from one of the clutch cones 24, 25 and engages it with the other, thereby reversing the direction of drive of the shaft 10 and the direction of motion of the carriage 29. A similar stop is provided on the shaft 28 at the other end of the machine, both stops being adjustable to accommodate the traverse of the carriage 29 to the width of the fabric being knitted.

By these means the carriage 29 together with the lamp 31 and photo-electric cell 32 are traversed to and fro across the width of the fabric 6 so that any undue irregularity in the opacity of the fabric 6 gives rise to a variation in the intensity of the light received by the cell 32.

Figure 3 is a general view showing how the mechanism is fitted to the frame of a straight bar warp knitting machine. The frame 12 carrying the shafts 10 and 28 is secured at 35 to the vertical brackets carrying the fabric roll 8 and at 36, 37 to the end frame of the machine. The

photo-electric cell 32 is connected by a suitable cable to an amplifier in the manner described hereafter with reference to Figures 4 and 5, the amplifier being adapted to intensify small variations of current occurring as the resistance of the cell 32 varies, and to employ the amplified current either to stop the machine or to give a warning signal when a fault in the fabric has occurred.

Referring to Figures 4, 5 and 6 the knitting elements 1 and 4 are shown as in Figure 1. In the form of apparatus shown in these figures no focused illumination is employed, the general illumination of the upper surface of the fabric 6 being relied on for the purposes of the invention. Below the fabric 6 as it leaves the needles 1 is disposed a photo-electric cell 41 mounted on a carriage 42 which slides on two horizontal angle bars 43 extending across the width of the machine. The bars 43 are carried at intervals on rods 44 secured to a cross-member 45 connecting the frames 13 of the machine.

The carriage 42 is driven by means of a double chain 46 passing round pulleys 47 at each end of the machine, the pulley 47 shown in Figures 4 and 5 being mounted on a shaft 48 carrying a bevel gear 49. The bevel gear 49 engages with the bevel gear 50 mounted on a shaft 51, which is carried in bearings 52 secured to the under side of the bars 43. The shaft 51 is driven by means of pulleys 53 and 54 from the hand-wheel shaft 14 of the machine.

The carriage 42 is connected to one run or the other of the double-chain 46 by means of a half sprocket 56 freely mounted on a spindle 57 secured to the top plate 58 of the carriage 42. The sprocket 56 has a projection 59 adapted to engage with one or other of two pins 60, 61 which project downwardly from a slide 62. The slide 62 is held against the under side of the top plate 58 by means of a guide-member 63, the spindle 57 passing through an elongated hole 64 in the slide 62. At each end of the machine is provided a stop pin 66 carried on a bracket 67 mounted on a shaft 68 extending across the machine. When the carriage 42 reaches the end of its travel across the machine the stop pin 66 engages the slide 62 and holds it still while the carriage 42 continues its motion. In this way the extension 59 on the half sprocket 66 disengages the pin 60 with which it is engaged and is free to rotate until it engages the other pin 61. The half sprocket 56 is thus permitted to rotate one half a revolution whereby its teeth disengage one run of the chain 46 and engage the other. Further rotation of the sprocket 56 is then prevented and the carriage 42 is effectively secured to the other run of the chain 46 whereby it is driven in the opposite direction. The positions of the brackets 67 and stops 66 are adjustable, in accordance with the width of the fabric being knitted.

The photo-electric cell 41 is thus driven backward and forward across the width of the fabric and receives light passing through the fabric. The light enters the cell by a slit 69 which is of such a length that every part of the fabric passes beneath it at some stage. That is to say, the length of fabric produced while the photo-electric cell crosses the fabric in both directions is less than the length of the slit 69. In this way every part of the fabric is scanned twice and, in the event of a missing thread, an extra thread, or any other fault there is a variation in the

amount of light entering the cell 41 whereby the resistance of the cell is varied.

The cell is supplied with current through a cable 70 mounted on a spring loaded drum 71 which allows the cable to be drawn off as the carriage 42 passes from right to left and collects the cable as the carriage passes from left to right. The drum 71 is shown in Figure 5 as being on the right hand side of the machine, the cable 70 passing from it, beneath the fabric, to the carriage 42. In the mechanism shown in Figures 1 to 3, the drum may be similarly disposed, or alternatively, since the cable 70 in this case passes over the fabric, it may be disposed in the middle of the length of the machine above the fabric. The end of the cable 70 is led inwards to the centre of the drum where it is connected by suitable leads 72 to an amplifier which intensifies the variations in current passing through the cell 69 and enables those variations to stop the machine and/or to exhibit a warning signal.

Having described our invention, what we desire to secure by Letters Patent is:

1. A stop or detector motion for a knitting machine comprising a photo-electric cell, means for traversing said cell repeatedly across the fabric being formed on the machine and close to the line at which the said fabric is being knitted, means for directing light coming from said fabric into said cell, and operative means controlled by said cell and adapted to give a warning indication on undue variation of the amount of light entering said cell by reason of faulty fabric.

2. A stop or detector motion for a knitting machine comprising a photo-electric cell, means for traversing said cell repeatedly across the fabric being formed on the machine and close to the line at which the said fabric is being knitted, means for directing light coming from said fabric into said cell, and operative means controlled by said cell and adapted to stop the machine on undue variation of the amount of light entering said cell by reason of faulty fabric.

3. A stop or detector motion for a knitting machine comprising a photo-electric cell, means for traversing said cell repeatedly across the fabric being formed on the machine and close to the line at which the said fabric is being knitted, means for directing a focused illumination through said fabric and into said cell, and operative means controlled by said cell and adapted to give a warning indication on undue variation of the amount of light entering said cell by reason of faulty fabric.

4. A stop or detector motion for a knitting machine comprising a photo-electric cell, means for traversing said cell repeatedly across the fabric being formed on the machine and close to the line at which the said fabric is being knitted, a mirror on the opposite side of said fabric to said cell, means for directing a focused illumination through said fabric to said mirror in such a way that said illumination is reflected from said mirror again through said fabric and into said cell, and operative means controlled by said cell and adapted to give a warning indication on undue variation of the amount of light entering said cell by reason of faulty fabric.

5. A stop or detector motion for a knitting machine comprising a photo-electric cell, means for traversing said cell repeatedly across the fabric being formed on the machine and close to the line at which the said fabric is being knitted, means for directing light coming from said fabric into said cell, said cell having a narrow slit disposed parallel to the length of said fabric for admitting said light, and operative means controlled by said cell and adapted to give a warning indication on undue variation of the amount of light entering said cell by reason of faulty fabric.

6. A stop or detector motion for a knitting machine comprising a photo-electric cell, means for traversing said cell repeatedly across the fabric being formed on the machine and close to the line at which the said fabric is being knitted, means for directing light coming from said fabric into said cell, means for adjusting the sensitivity of said cell, and operative means controlled by said cell and adapted to give a warning indication on undue variation of the amount of light entering said cell by reason of faulty fabric.

7. A stop or detector motion for a straight bar knitting machine comprising a photo-electric cell, means for traversing said cell repeatedly to and fro along a straight line across the fabric being formed on the machine and close to the line at which the said fabric is being knitted, means for directing light coming from said fabric into said cell, and operative means controlled by said cell and adapted to give a warning indication on undue variation of the amount of light entering said cell by reason of faulty fabric.

8. A stop or detector motion for a straight bar knitting machine comprising a photo-electric cell, means for traversing said cell repeatedly to and fro along a straight line across the fabric being formed on the machine and close to the line at which said fabric is being knitted, means for directing a focused illumination through said fabric and into said cell, said cell having a narrow slit disposed parallel to the length of said fabric for admitting said light, and operative means controlled by said cell and adapted to stop the machine on undue variation of the amount of light entering said cell by reason of faulty fabric.

9. A stop or detector motion for a straight bar knitting machine comprising a photo-electric cell, means for traversing said cell repeatedly to and fro along a straight line across the fabric being formed on the machine and close to the line at which said fabric is being knitted, a mirror on the opposite side of said fabric to said cell, means for directing a focused illumination through said fabric to said mirror in such a way that said illumination is reflected from said mirror again through said fabric and into said cell, said cell having a narrow slit disposed parallel to the length of said fabric for admitting said light, and operative means controlled by said cell and adapted to stop the machine on undue variation of the amount of light entering said cell by reason of faulty fabric.

50 10 15 20 25 30 35 40 45 50 55 60 65

10. A stop or detector motion for a straight bar knitting machine comprising a photo-electric cell, means for traversing said cell repeatedly to and fro along a straight line across the fabric being formed on the machine and close to the line at which said fabric is being knitted, a mirror on the opposite side of said fabric to said cell, means for directing a focused illumination through said fabric to said mirror in such a way that said illumination is reflected from said mirror again through said fabric and into said cell, said cell having a narrow slit disposed parallel to the length of said fabric for admitting said light, and operative means controlled by said cell and adapted to stop the machine on undue variation of the amount of light entering said cell by reason of faulty fabric.
